No. 416.

Geo. R. Phillips' Cabinet Design

Dated September 30, 1857. —

Des. 416

Ezra Ripley, of Troy, N.Y.
Letters Patent No 416. Dated, Sept. 30, 1851.

The schedule referred to in these Letters Patent and marking
part of the same.

To all to whom these presents shall come:

Be it known,
that I, Ezra Ripley of Troy in the county of Rensselaer, and
state of New York, have invented or produced a new design of

parlour stove, which I call the grecian parlour, and I do hereby declare that the following is a full & exact description of the same reference being had to the annexed drawing, making a part of this specification, which is a perspective view of my stove front which is all I intend to secure by letters patent.

The front has two sets of double doors A A & B B, ornamented as represented, & a corner C, ornamented with rosettes D D & various arabesques figures E E, as represented in the drawing).

What I claim & desire to secure by letters Patent is the design & configuration of parlour stove fronts, substantially the same as described and represented.
